(57) **CLAIM**

The ornamental design for a food pan support rail, as shown and described.

DESCRIPTION

FIG. 1 is a frontal perspective view of the food pan support rail from the left side thereof.

FIG. 2 is a left side elevation view thereof.

FIG. 3 is a right side elevation thereof.

FIG. 4 is a front elevation view thereof.

FIG. 5 is a top plan view thereof.

FIG. 6 is a rear elevation view thereof; and,

FIG. 7 is a bottom plan view thereof.

The double lines signifying a break are indicative of indeterminate length.
